(57) **CLAIM**

The ornamental design for a ink cartridge, as shown and described.

DESCRIPTION

FIG. 1 is a front perspective view of an ink cartridge;

FIG. 2 is a top view thereof; and,

FIG. 3 is a right-side view thereof.

The broken lines are for illustrative purposes only and form no part of the claimed design.

1 Claim, 1 Drawing Sheet

FIG. 1

FIG. 2

FIG. 3
